(57) **CLAIM**

The ornamental design for a surgical hood, as shown and described.

DESCRIPTION

FIG. 1 is a rear bottom perspective view of a surgical hood showing our new design;

FIG. 2 is a bottom right-side perspective view thereof;

FIG. 3 is an enlarged perspective view thereof depicting the circled portion of FIG. 2;

FIG. 4 is a bottom left-side perspective view thereof;

FIG. 5 is a partial front-side view thereof shown in a flattened position;

FIG. 6 is a front-side view thereof;

FIG. 7 is a left-side view thereof;

FIG. 8 is a rear-side view thereof;

FIG. 9 is a right-side view thereof;

FIG. 10 is a top-side view thereof;

FIG. 11 is a bottom-side view showing an interior portion of the surgical hood;

FIG. 12 is a side perspective view of the surgical hood in an inside-out configuration; and,

FIG. 13 is a partial front-side view of the inside-out configuration of the surgical hood shown in a flattened position. The broken lines in dash-dot-dot format in FIG. 5 and FIG. 13 represent an enlarged portion of the claimed design but not a boundary of the claimed design. All other evenly broken lines represent portions of the surgical hood that form no part of the claimed design.
